UNITED STATES PATENT OFFICE.

GROVER C. MCLEAN, OF WHITEWRIGHT, TEXAS.

FIREARM.

1,181,024.

Specification of Letters Patent.

Patented Apr. 25, 1916.

Application filed November 16, 1915. Serial No. 61,808.

To all whom it may concern:

Be it known that I, GROVER C. MCLEAN, a citizen of the United States, residing at Whitewright, in the county of Grayson and State of Texas, have invented certain new and useful Improvements in Firearms, of which the following is a specification.

The present invention has to do generally with the art of firearms and in particular with magazine rifles, the object in view being to improve certain features of the working mechanism by means of which the cartridges are transferred successively from the magazine to the rifle barrel and extraction and ejection of said cartridges therefrom.

The essence of the invention lies especially in the provision of a novel form of cartridge carrier or lifter and the actuating means therefor whereby upon firing of the rifle, said carrier is initially operated directly by the hammer, first to release its coöperating action-bar and secondly, to interlock a cartridge with the breech block, then subsequently actuated by said action-bar during one direction of its movement to bring the cartridge into receiving position and finally operated to insert said cartridge into engagement with the gripping and ejecting elements of said breech block for driving home into the barrel upon movement of the action-bar in the direction opposite to that just mentioned.

A further object has reference to the safety locking means whereby certain features in common with the cartridge carrier are provided, thereby simplifying and rendering the mechanism more compact.

With the above and such other objects as may hereinafter appear in view, this invention consists in the construction, combination and arrangement of parts all as herein-after more fully described, claimed and illustrated in the accompanying drawings, wherein:

Figure 1 is a side elevation of an embodiment of my invention. Fig. 2 is a longitudinal sectional view with parts in position preliminary to firing, dotted lines showing the hammer and cartridge carrier in the position assumed subsequent to firing. Fig. 3 is a similar sectional view with the breech block in open position and other parts correspondingly disposed. Fig. 4 is a longitudinal sectional view showing the mechanism subsequent to cocking the rifle and with the breech block partly moved

into closed position. Fig. 5 is a vertical sectional view taken on the line 5—5 of Fig. 4. Fig. 6 is a longitudinal sectional view of the right side of the receiver frame. Figs. 60 7 and 8 are vertical sectional views on the lines 7—7 and 8—8 respectively of Fig. 6. Figs. 9 and 10 are reverse elevations of the breech block. Figs. 11 and 12 are front elevation and top plan views respectively of 65 the breech block, certain parts in the latter view being broken away to show more clearly the cartridge grip pieces. Fig. 13 is a side elevation of the stock section of the receiver frame. Figs. 14 and 15 are reverse 70 elevations of the cartridge carrier. Figs. 16 and 17 are side elevation and top plan views respectively of the action-bar, certain parts in the latter view being broken away to show the spring actuated dog. Fig. 18 is 75 a detail view of the rear end portion of the barrel. Fig. 19 is a detail view of the trigger and safety locking device therefor. Fig. 20 is a fragmentary view of the outer magazine tube; and Fig. 21 is a longitudinal sectional view of the inner magazine tube. 80

Throughout the following detail description, and on the several figures of the drawings, similar parts are referred to by like reference characters.

Specifically describing the invention and referring to the drawings, the numeral 1 designates the stock section of the receiver frame having mounted therein the hammer 2 and the trigger 3. Said hammer is 90 adapted to be actuated by means of the spindle 4 detachably connected at the rear of the hammer and surrounded by a spring 5 for throwing the hammer upon release thereof through the instrumentality of the trigger 95 in the customary manner. To the forward portion of the receiver frame the rifle barrel 6 is connected in the usual manner and directly in rear of the bore 7 of the barrel is reciprocatingly mounted the breech block 100 8, said breech block being most distinctly disclosed in Figs. 9 to 12 of the drawings. It will be noted that the breech block is longitudinally grooved to receive a spring 105 retracted firing pin 9, the rear extremity of which projects a short distance beyond the body of the breech block. At the forward extremity of said breech block are mounted oppositely disposed, yieldable grip members 10, 11, actuated by a spring 12 common to 110 both. It may be mentioned at this point that the hooked extremity of the grip piece

10 is of such construction as to constitute a positive gripping element engageable with the rim of the head of a cartridge in carrying out the operation of this invention. The 5 corresponding grip piece 11 is similar in construction excepting that its hooked extremity is of such a shape as to permit the displacement of the cartridge therefrom while being held positively by its co-operating grip piece 10 such that a lateral whirling action is obtained in the ejection of the cartridge from the gun as will be more particularly described hereinafter. The firing pin 9 is adapted at its forward end to project between the grip pieces and the ejection of the cartridge takes place when the breech block is moved rearwardly in the receiver frame and the rear extremity of the firing pin abuts against the rear wall of the receiver frame or section 1, such impingement causing the firing pin to contact with the cartridge and eject the same laterally through the side opening 13 of the barrel frame section 14. The face of the breech block, furthermore, is suitably grooved as indicated at 15 beneath the grip pieces 10 and 11 so as to guide the cartridge from the magazine to said grip pieces through the instrumentality of the cartridge carrier hereinafter described. The forward portion of the barrel section 14 is provided with a short passage 16 which communicates with the magazine for the rifle of which 17 designates the outer shell and 18 the inner shell, 30 said magazine being provided with the usual follower 19, all of conventional construction so that no further description is deemed necessary in respect to this feature.

Reverting to the breech block it will be observed that its forward end is provided with spaced legs 20, 21, the latter being longer than the first mentioned leg for reasons which will appear hereinafter. In addition the breech block at its upper portion is 45 formed with a recoil projection or lug 22 which in closed position of the breech block is received in the recoil recess 23 formed in the barrel section of the receiver. Both the receiver frame and stock sections are 50 grooved as indicated at 24 in Fig. 8 of the drawings to receive the breech block for reciprocation and it will be apparent that this is advantageous in that it prevents the accidental displacement of the breech block 55 when dismantling the rifle for repair or cleaning purposes.

The breech block is adapted to be reciprocated or actuated by means of the action-bar or slide 25 shown most clearly in Figs. 60 16 and 17, the forward end of said action-bar being connected to the grip piece or forearm 26. The action-bar is longitudinally grooved at its rear portion as indicated at 27 and one of the side members thereof 65 carries the spring actuated dog 28, the ex-

tremity of which projects laterally into the slot 27. The opposite leg of the action-bar has formed in its upper surface a recess 29 which conforms in shape and configuration to the cam extension 21' of the leg 21 of the breech block. The last-mentioned leg of the action-bar is longer than the one carrying the dog 28 and thereby provides an extension 25 upon which the cam extension 21' of the breech block normally seats so that when 70 said breech block is in closed position the recoil projection 22 is held in the recess 28. The cam extension 21' and its corresponding recess 29 in the action-bar constitutes the operative connection between the action bar 75 and the breech block by means of which the latter is reciprocated, primarily for the purpose of cocking the gun and for reloading the same in a manner quite customary in devices of this character. 80

One of the main features of this invention is the cartridge carrier or lifting member now to be described.

It will be observed by reference to Figs. 14 and 15 that the carrier 30 at its forward end is provided with a hook-shaped element 31 which is formed by slotting the body of the material from which it is made as indicated at 32. Leading to this slot across the neck of the hook element 31 is a lateral groove 33 and adjacent to the opposite end of said slot 32 the carrier is formed with a lower projection or extension constituting a cam 34. This cam is also formed with a lateral groove 35. 90

Referring now to Fig. 2 of the drawing it will be observed that the carrier 30 is pivoted at 36 between the receiver sections and in advance of the hammer 2, said carrier being provided at its rear extremity with a projection 37 with which the recessed edge, indicated 38, of the hammer 2 is adapted to coact upon the release of said hammer as in the firing of the gun. The carrier 30 is normally disposed in the full line lowermost position shown in Fig. 2 of the drawing, in which position the head of the carrier lies at the opening of the slot 27 in the action-bar 25. In such normal position the dog 28 abuts against the edge of the forward extremity of the carrier, and, therefore, the action-bar is locked against sliding movement. Before describing the operation of these parts, it will be mentioned that the carrier 30 is held in its normal locking position by means of the spring 39 coacting with its rear extremity, said spring being disposed upon the upper end of a vertically arranged locking element 40 constituting a part of the safety locking mechanism for this construction. It will be noted in Fig. 19 that the element 40 is provided with an attenuated portion 41 extending through a slot 42 at the forward portion of the trigger 3 and disposed transversely of the trigger 100 115 120 125 130

at its extremity is a laterally shiftable pin 43 having a recessed portion 44 which coacts with the attenuated portion 41 of the piece 40 and a slot 45 through which the lower extremity 40' of said piece 40 extends into the trigger guard 3'. This safety locking arrangement is operated by shifting the pin 43 laterally until the recess 44 lies directly beneath the forward extension of the trigger 3, as seen in Fig. 5 most clearly where said trigger may be moved on its pivot and the gun fired. To lock the gun in safety position the pin 43 is moved laterally into the dotted line position shown in Fig. 5 until the recess 44 is out of registry with the trigger extension just mentioned. The advantage of the arrangement hereinbefore described is the provision of the spring 39 for the carrier member 30 whereby it is held in its normal position as well as for the plunger piece 40 of the safety locking device whereby the latter is held in proper position, the latter in turn holding the shifting pin 43 in place. This dispenses with the provision of a separate and independent spring for the carrier as will be apparent to those skilled in the art to which the invention refers. The trigger 3 is normally held in position by the spring 3'' coacting with 30 its forward extremity.

Describing the operation of this mechanism, and referring first to Fig. 2 of the drawings, when the gun is fired, and the hammer 2 thrown said hammer impinges against the rear extremity of the cartridge carrier 30 moving said carrier into the dotted line position whereby the action-bar 25 is released by reason of the fact that the lateral groove 33 of the carrier is brought into a position in registry with the dog 28 on said action-bar. In this position it will also be understood that the carrier is brought into contact with the cartridge which is held in position against the face of the breech block 8 by the magazine plunger 19, just above the forward end of the carrier 30 operating between the spaced legs 20 and 21 of said breech block. This initial movement of the carrier has, therefore, raised the rear end of this cartridge until it is engaged with the grooved face of the breech block. The action-bar 25 being free to move rearwardly by actuating the same through the instrumentality of the forearm 26, the dog 28 will ride over the neck of the cartridge carrier, by reason of the groove 33 until it drops into the cam slot 32 of the carrier. The dog 28 then acts upon the cam surface 32' of said carrier causing the carrier to be raised as the action-bar moves rearwardly. The cartridge in this second stage of lifting movement of the carrier rides upon the upper cam surface 32'' of said carrier until the cartridge is brought into position just below the grip pieces 10 and 11 of the breech block 8. Upon the initial movement of the action-bar 25 the cam extension 21' of the breech block moves downwardly into the recess 29 of the action-bar, thereby dropping the recoil projection from engagement with the wall of the recess 23 and operatively connecting the breech block to the action-bar for movement rearwardly therewith. As the breech block reaches its rearmost position shown in Fig. 3, the empty cartridge held by the gripping elements of the breech block is ejected in the manner hereinbefore clearly described. Furthermore, the dog 28 having reached in this rearward movement of the action-bar and breech block, the cam extension 34 on the carrier is caused to ride thereover through the lateral groove 35 of said extension until it engages the rear cam surface of this extension 34. The action-bar 85 is now moved in the opposite direction by the operator whereupon the dog 28 acting upon the cam extension 34 just mentioned imparts the third degree of movement to the carrier which is an abrupt movement causing said carrier to shift the cartridge, which has been moved up the face of the breech block, into position between the grip pieces 10 and 11 thereof, said grip pieces positively holding the cartridge in position for 95 introduction into the bore 7 of the barrel when the breech block has been moved into closed position shown in Fig. 2. Fig. 4 shows the breech block in its partial movement forwardly into the closed position just referred to with the cartridge about to enter the bore of the rifle and the carrier in its uppermost position. On this return movement of the breech block the dog 28 passes off of the cam extension 34 whereupon the 100 carrier 30 is suddenly moved to its normal position with its forward extremity locking the action-bar and beneath the succeeding cartridge passing from the magazine into position against the face of the breech block. The dropping of the carrier is caused in 105 this mechanism, by reason of the fact that the upper edge of the carrier is provided with an additional cam surface 32'' which is impinged by the breech block when it is moving forwardly and in the meantime the dog 28 which has reached the slot 32, engages on top of the hook extremity, riding therealong and causing the carrier to gradually reach its initial position. When the 110 carrier reaches its lowermost position the spring 39 tends to hold it there. In the upward movement of the carrier 30, the forward extremity receives thereagainst the cartridge which is projected from the magazine to take the place of the one which is being lifted into the receiving position upon the breech block and this forward end holds said cartridge from jamming or projection from the magazine at an improper time, or 115 120 125 130

until said carrier drops to its normal position shown in full lines in Fig. 2.

The breech mechanism of this invention is adapted to be manually released and for this purpose the receiver frame is formed with a chamfered recess 46 therebeneath whereby the operator may press upwardly on the carrier 30 until the action-bar is released in the manner hereinbefore described. This enables the ejection of a bullet that may not be desired where different length bullets are employed or in the event other operations incidental to cocking of the gun, etc., may be desired.

Having thus described my invention, what I claim is:

1. In a firearm of the class described, the combination of a breech block, a hammer, an action-bar coöperative with the breech block, and a cartridge carrier normally holding the action bar inoperative and disposed in the path of movement of the hammer aforesaid for impingement by said hammer to release the action bar.

2. In a firearm of the class described, the combination of a breech block, a hammer, an action-bar coöperative with the breech block, and a locking member for holding the action bar inoperative and disposed in the path of movement of the hammer aforesaid for impingement by said hammer to release the action bar, said locking member incident to the actuation thereof by the hammer coating with a cartridge to cause engagement of said cartridge with the breech block.

3. In a firearm of the class described, the combination of a breech block, a hammer, an action-bar coöperative with the breech block, and a locking member normally engageable with the action bar to hold the same inoperative and pivotally mounted in advance of the hammer whereby upon firing movement of said hammer, the locking member is impinged at one end to impart lifting action to a cartridge engageable by its other end.

4. In a firearm of the class described, the combination of a breech block, a hammer, an action-bar coöperative with the breech block, a cartridge carrier arranged intermediate the hammer and action-bar, said carrier being initially operable by the hammer to release the action-bar and simultaneously shift a cartridge into engagement with the breech block, means for imparting lifting movement to the carrier and incidentally to the cartridge also, and means coöperative with the last-mentioned means for lifting the carrier a further degree to shift the cartridge into position for delivery by the breech block.

5. In a firearm of the class described, the combination of a breech block, a hammer, a cartridge carrier arranged to be initially

operated by the hammer for engaging the carrier with a cartridge, means engageable with the carrier for imparting lifting action thereto, and a cam member on said carrier with which said means is adapted to coöperate to impart final lifting action to said carrier.

6. In a firearm of the class described, the combination of a breech block, a hammer, a cartridge carrier arranged to be initially operated by the hammer for engaging the carrier with a cartridge, reciprocating means engageable with the carrier in one direction of movement of said means to impart lifting action to the carrier, and means on the carrier with which the reciprocating means engages in its other direction of movement to impart final lifting action to the carrier.

7. In a firearm of the class described, the combination of a breech block, a hammer, a cartridge carrier arranged for impingement by the hammer to impart releasing movement to said carrier and simultaneous engagement thereof with a cartridge, a reciprocating action-bar normally held inoperative by the carrier, a dog on said action-bar engageable with the carrier to shift the cartridge, and a cam on said carrier controlling final shifting of the cartridge into delivery position on its breech block.

8. In a firearm of the class described, the combination with an action-bar and a spring actuated lifting dog carried thereby, of a cartridge carrier pivotally mounted for co-operation with said action-bar, said carrier having a cam slot to receive the dog for actuating the carrier, and a cam projection arranged in the path of said dog to actuate said carrier subsequent to the initial actuation by the dog.

9. In a firearm of the class described, the combination with an action-bar and a spring actuated lifting dog carried thereby, of a cartridge carrier pivotally mounted for co-operation with said action-bar, said carrier having a cam slot to receive the dog for actuating the carrier, said carrier having a lateral groove leading to the slot to allow the dog to enter said slot without lifting the carrier, and a cam extension having a lateral groove to permit the dog aforesaid to ride over said extension into operative position with respect to the cam surface of said extension.

10. In a firearm of the class described, the combination with a sliding action-bar and a spring actuated lifting dog carried thereby, of a cartridge carrier pivotally mounted adjacent to the action-bar, said carrier having a cam slot at the end portion thereof to receive the dog for gradual lifting movement of said carrier upon movement of the action-bar in one direction, and a cam extension arranged on the carrier adjacent to the

end of said slot for coöperation with the dog whereby to impart abrupt lifting action to the carrier upon movement of the action-bar in the opposite direction.

5 11. In a firearm of the class described, the combination of a breech block, a hammer, an action-bar coöperative with the breech block, and a cartridge carrier having one end disposed in the path of movement of 10 the action bar whereby to hold said bar against movement normally and its other end arranged in the path of movement of the hammer, said carrier being operable by the hammer to simultaneously release the 15 action bar and impart lifting movement to a cartridge.

12. In a firearm of the class described, the combination of a receiver frame, a breech block slidingly mounted therein, means for 20 guiding said breech block in its reciprocating movement, an action-bar adapted to be operatively connected with said breech block for reciprocating the same, a hammer mounted in said frame, a cartridge carrier 25 disposed intermediate the hammer and the action-bar, said carrier being operable upon throwing of the hammer to impart initial lifting movement thereto, means on the action-bar for raising said carrier a second 30 degree of movement upon movement of the action-bar in one direction, and means on the carrier with which the last mentioned means coacts to impart final lifting movement to 35 said carrier upon movement of the action-bar in the opposite direction, said action bar raising means positively returning the carrier to its normal inoperative position.

13. In a firearm of the class described, 40 the combination of a receiver frame, a breech block slidingly mounted therein, means for guiding said breech block in its reciprocating movement, an action-bar adapted to be operatively connected with said breech

block for reciprocating the same, a hammer 45 mounted in said frame, a cartridge carrier disposed intermediate the hammer and the action-bar, said carrier being operable upon throwing of the hammer to impart initial lifting movement thereto, means on the action-bar for raising said carrier a second degree of movement upon movement of the action-bar in one direction, means on the carrier with which the last mentioned means coacts to impart final lifting movement to 50 said carrier upon movement of the action-bar in the opposite direction, and spring means for holding the carrier in its normal inoperative position, said carrier being arranged for impingement by the breech block 55 and reengagement by the action-bar raising means to return the carrier to the last-mentioned position.

14. In a firearm of the class described, the combination of a receiver frame, a hammer 65 mounted therein, a trigger for controlling the action of said hammer, an action bar, a locking member therefor, means for holding said locking member in locking position, and a safety device for locking said trigger 70 with which the holding means last mentioned coöperates.

15. In a firearm of the class described, the combination of a receiver frame, a hammer mounted therein, a trigger for controlling 75 the action of said hammer, an action-bar, a locking member therefor, means for holding said locking member in locking position, and a safety locking device including a plunger member coacting with the trigger 80 and a locking element with which said plunger coacts to release the trigger, said plunger being held in position by the holding means for the action-bar locking member.

In testimony whereof I affix my signature.

GROVER C. McLEAN.
